UNITED STATES PATENT OFFICE

132,472

DESIGN FOR A GLOVE

Ernest R. Schraps, New York, N. Y.

Application January 30, 1942, Serial No. 105,521

Term of patent 3½ years

To whom it may concern:

Be it known that I, Ernest R. Schraps, a citizen of the United States, residing at Manhattan, in the city, county, and State of New York, have invented a new, original, and ornamental Design for a Glove, of which the following is a specification, reference being had to the accompanying drawing, forming part thereof.

Fig. 1 is a rear view of a glove showing my new design with the first, fourth, and fifth fingers in clenched position, and

Fig. 2 is a front view of the glove shown in Fig.

1 with the first, fourth, and fifth fingers in clenched position.

The characteristic feature of my design resides in the combination on a glove of the contrast on the back of the index and adjacent fingers and extending over the knuckles so as to form the latter V as shown.

I claim:

The ornamental design for a glove, substantially as shown and described.

ERNEST R. SCHRAPS.
